W. H. ELLINGER

ROLLER BEARING SWIVEL WRENCH PLATE

Filed Aug. 1, 1921

UNITED STATES PATENT OFFICE.

WILLIAM H. ELLINGER, OF WICHITA FALLS, TEXAS.

ROLLER-BEARING SWIVEL WRENCH PLATE.

Application filed August 1, 1921. Serial No. 489,036.

To all whom it may concern:

Be it known that I, WILLIAM H. ELLINGER, a citizen of the United States of America, residing at Wichita Falls, in the county of 5 Wichita and State of Texas, have invented certain new and useful Improvements in Roller-Bearing Swivel Wrench Plates, of which the following is a specification.

My invention relates to roller bearing 10 swivel wrench plates and more particularly to certain controlling and locking means; and the objects are to safety swivel wrench plates for use with any suitable fishing tool or bit for use in oil fields and water well 15 drilling which tool or wrench plate is provided with certain safety appliances to prevent the wrench plate from releasing the fishing tool or bit. A further object is to provide certain improvements which will 20 make the wrench plate easily operated and to provide the plate with roller bearings and means for preventing the loss of the roller or ball bearings when the plate is being knocked down or separated and 25 when the wrench plate is being assembled. Other objects and advantages will be fully explained in the following description and the invention will be more particularly pointed out in the claims.

Reference is had to the accompanying drawings which form a part of this application.

Fig. 1 is a plan view of the wrench plate assembled. Fig. 2 is a plan view, partly 35 swung open, to illustrate the locking means. Fig. 3 is a front elevation of the wrench plate assembled. Fig. 4 is a vertical section, taken on the line 4—4 of Fig. 1. Figs. 5 and 6 are different views of the ball bearing lock shown on the right sides of the views in Figs. 1, 2, and 3. Fig. 7 illustrates plates or bushings for attaching to the main tool when the main tool is too large for some 40 special size bit or fishing tool. Fig. 8 is detail view, showing the construction of the ball and socket joint.

Similar characters of reference are used to indicate the same parts throughout the several views.

50 The improved wrench plate is provided with a support which includes a handle 1 and curved arms 2 and 3, the terminals of which constitute trunnion bearings 5. The arms 2 and 3 are hingedly connected by a tongue and groove joint 4, and pivot or locking bolt 6. The bit or tool engaging

member is in two parts 7 and 8 hingedly connected together at their rear sides by a tongue and groove joint 9 and pivot bolt 10. The members 7 and 8 have depending 60 handle members 11 and these handles may be bolted and made rigid with the members 7 and 8 but the handles 11 must move freely within the supports 13 and 14. The members 7 and 8 have grooves in their under 65 faces for ball bearings 12. The bit or tool engaging members 7 and 8 are carried by co-operating curved supports 13 and 14 which are hingedly connected at their rear sides by a tongue and groove joint 15 and 70 pivot bolt 16. The supports 13 and 14 have curved grooves in their upper faces for the ball bearings 12. With such construction, the swivel bit or tool engaging members 7 and 8 are easily turned or adjusted on the 75 supports 13 and 14, and in this manner the bit or fishing tool can be adjusted to the required positions. The supporting members 13 and 14 are mounted on trunnions 17 which are carried in the bearings 5 of the arms 2 80 and 3. By means of the trunnions 17, the engaging members 7 and 8 and their supporting members 13 and 14 having a rocking motion are adapted to be turned so that the bit or tool may be engaged at different 85 angles or positions. The trunnions 17 have balls 29 formed on their outer ends and are held in the supports 2 and 3 or their bearings 5 by caps 30. The trunnions 17 have annular grooves 19 near their ends and locking studs 20 are screwed into the supporting 90 arms 13 and 14 and projected into the grooves 19 so that the trunnions 17 cannot be displaced in operation. The openings in the supports 13 and 14 for the trunnions 17 are 95 enlarged horizontally, as shown at 21, so that the trunnions 17 can have enough movement to permit the tool to be opened to receive a bit or fishing tool. The devices are partly opened in Fig. 2. The supporting members are connected at their front 100 sides by a tongue and groove joint 22 and this joint is locked by a specially constructed locking device. The same locking device serves to lock the balls 12 in their race. A 105 bolt 23 has a groove 24 in its upper face corresponding in contour to the groove in member 14. When the device is locked in operative position, the balls 12 will run through the groove 24 just as in the grooves 110 in members 13 and 14. The bolt 23 occupies the opening 25 in the locked position, as in

Figs. 1 and 3. The bolt 23 is cut away to form a neck 26 or narrow portion so that the bolt may be turned one quarter turn to permit the tongue 22 to be withdrawn from its locked position when the tool is to be opened. The tongue 22 has a slot from the opening 25 to the end so that the tongue can be drawn away from the bolt 23, the neck 26 passing through the slot. Fig. 6 shows the bolt in the locked position as in Fig. 3 and the tongue 22 cannot be withdrawn because the neck 26 is standing with the broad side towards the slot in tongue 22. When the bolt 23 is turned a quarter turn to permit the tongue 22 to be withdrawn, the groove 24 is turned cross-wise the groove in member 14 so that the balls 12 cannot pass. The balls are thus locked in place, as shown by the bolt 27 in Fig. 2, the groove in the head of the bolt being turned cross-wise the groove in member 13.

Cavities are made in the faces of bearings 5 and caps 30 to form sockets for the balls 29 on trunnions 17. The caps 30 are bolted to the bearings 5 by bolts 18.

For adapting the tool herein described for bits or fishing tools of smaller size, bushings or plates 28 may be bolted to the members 7 and 8. The bushings have smaller opening therethrough than the opening in the members 7 and 8.

What I claim is—

1. A swivel wrench plate comprising a carrier in two parts consisting of curved arms hingedly connected together, a wrench plate support consisting of two curved members hingedly connected together at their rear sides and having a detachable tongue and groove connection at their front sides, trunnions for mounting said curved supporting members on said curved arms having ball and socket connections with said curved carrier arm, and a wrench plate rotatably mounted on said support and consisting of two members hingedly connected at their rear edges.

2. A swivel wrench plate comprising a carrier, a wrench plate support consisting of two curved members hingedly connected at their rear sides and having a detachable connection at their front sides and said members having a continuous curved groove in their upper faces when locked together, trunnions for supporting said wrench plate having ball and socket connections with said carrier, a tool engaging member in two parts hingedly connected together at their rear sides and having a continuous curved groove in their under faces when in operative position, ball bearings mounted in the curved grooves between said support and said tool engaging member, and handles for said tool engaging member projecting down through said support.

3. A swivel wrench plate comprising a

carrier composed of two curved arms hingedly connected together, a support composed of two curved members hingedly connected together at their rear edges and detachably connected at their front edges, trunnions 70 having ball and socket connections with said curved carrier arm and pivotally connected with the curved arms of said support, and means for locking said trunnion against removal from said pivotal connections, a tool engaging member in two parts hingedly connected together at their rear sides, said tool engaging member and said support having curved grooves forming a ball bearing race between their meeting 75 faces, and handles for said tool-engaging member projected down through said support.

4. A swivel wrench plate comprising a carrier composed of two curved arms hingedly connected together and provided with bearing terminals, tool supporting and operating members hingedly connected together at their rear sides and detachably connected at their front sides, trunnions 80 having balls at one end mounted in said terminals and having the other ends inserted in said tool supporting members, means for holding said balls in said terminals, and means preventing the removal of said trunnions from said supporting and operating members.

5. A swivel wrench plate having a carrier, a supporting member pivotally mounted in said carrier, a tool engaging member mounted on said supporting member, said supporting member and said tool engaging member having concentric grooves in their adjacent faces, ball bearings mounted in said grooves, and means for locking said ball bearings in said grooves when said members are opened to receive a tool, including bolts having grooves corresponding to the grooves in said supporting member.

6. A swivel wrench plate having a carrier, a supporting member pivotally mounted in said carrier, a tool engaging member mounted on said support, said members having grooves in their adjacent faces constituting a ball bearing race, ball bearings in 115 said race, and means for locking said balls in said race when said members are opened to receive a tool and for releasing a tool consisting of bolts provided with heads having grooves therein corresponding to the 120 grooves in said members and forming a part of said race and adapted to be turned one quarter turn and form stops in said race.

7. A swivel wrench plate having a carrier, a supporting member mounted on said carrier, a tool engaging member mounted on said support, said members having grooves in their adjacent faces forming a race for ball bearings, ball bearings in said race, and means for locking said balls in 130

said race when said members are to be opened consisting of bolts having heads provided with grooves therein corresponding to the grooves forming said race and forming a part of said race and adapted to be turned one quarter turn and form stops in said race and one of said bolts normally lock-

ing said supporting member in operative position but releasing the parts forming said support when turned to lock said balls 10 in said race.

In testimony whereof, I set my hand, this 20th day of July, 1921.

WILLIAM H. ELLINGER.
